A. J. COOK

TWO-PIECE RAIL ANCHOR

Original Filed June 14, 1926

UNITED STATES PATENT OFFICE.

ADONIRAM J. COOK, OF WESTERLO, NEW YORK, ASSIGNOR TO THE P & M COMPANY, OF CHICAGO, ILLINOIS, A CORPORATION OF ILLINOIS.

TWO-PIECE RAIL ANCHOR.

Application filed June 14, 1926, Serial No. 115,914. Renewed January 22, 1927.

As is well known by those engaged in railroad operation, the general causes of rail creeping are: the wave motion of the track under the alternate application and release 5 of a rolling load; the application of the brake, especially when the wheels slide; curvature of the track when the velocity of the train is greater or less than the velocity for which the outer rail is elevated; and 10 descending grades. Rails creep also excessively on bridges.

The general object of my invention is the provision of an improved device which when 15 several thereof are combined with the track rails and cross ties will prevent the creeping or longitudinal movement of the rails relative to the ties under traffic. Its function is to hold the rail in a fixed position relative to the tie so that the force which causes creeping 20 of the rail will be transmitted through both the rail and tie to the track ballast.

The specific object is the provision of such a device which shall be simple in construction—in two pieces—cheaply produced, and 25 easily applied, and which shall be adapted to perform the requisite function.

The invention consists in the improved construction and in the combination of parts as herein set forth and claimed.

30 The accompanying drawing illustrates an example of the embodiment of the invention, the parts being constructed, formed, and combined according to the best mode of procedure I have so far devised for the purpose.

35 Figure 1 is a top plan view of part of a track tie and rail showing the anchor in position.

Figure 2 is a cross section in elevation of 40 Figure 1 on line 2—2.

Figure 3 is a perspective view of the wedging device.

Figure 4 is a perspective view of the anchor bar.

45 The numeral 5 designates the tie, and 6 and 7, the head and flanges of a track rail, of well known constructions.

The anchor bar consists of a bar of metal, 50 preferably of wrought metal or relatively soft steel, having the bent-over ends 14 and 15, the lever offset 18 and recess 16. The top surface of the bar is a flat surface and is parallel, longitudinally of the rail, to the bottom surface of the rail before the bar is

driven, as hereinafter described, into engagement with the wedge member. The body of the bar is bent at the point 13 so that the surfaces to the left and right of said point will lie in different planes angularly disposed to each other. However, if desired, the anchor bar may be made of resilient metals or of cast metal cast to the shape shown by Figure 4.

The wedging device, Figure 3, consists of a body portion U-shaped in cross section having the two flanges 9 and 11, and the bearing flange 12 disposed at one end of the body portion and at a right angle thereto. The outer surface of the flange 12 is plain and is adapted to frictionally engage the 55 vertical surface of the tie.

Special attention is called to the wedging surfaces of the wedging device. The bottom surface of flange 9 is inclined transversely of the wedge members so as to correspond with substantially the inclined portion 13^a of the anchor bar. The said lower surface of said flange also tapers longitudinally of the wedge member, that is to say, from the point 17 to the end 8 of the member. The surface 10 is inclined from the bearing flange 12 to the outer end of the body portion so as to provide a wedge surface adapted to bear against the inner surface of the hooked end portion 15. Note that the surface 10 and the under surface of the flange 9 are obliquely disposed with relation to the vertical plane of the bearing flange 12.

To apply the device to a rail, the anchor bar is preferably passed over the end of the rail to the desired position. It will be obvious, however, that the proportions of the yoke may be varied so that it may be hooked over the rail base, in a manner well understood, at points intermediate the ends of the rail. The wedging device is placed with the bearing flange abutting the tie. The end 15 of the bar is then slipped over the free 70 end of the wedging device as far as it will go without the application of much force.

The bar is then driven by a sledge to the relative position shown by Figure 1. In driving the bar to its seat the following actions take place: as the lower inclined surface of flange 9 engages the offset 18 of the anchor bar the portion 18 is forced downwardly and causes a longitudinal twisting of the bar so that the opposite inner sharp edges of the 75

turned-over end 14 engage the upper and lower surfaces respectively of the rail flange and bite into the metal, producing a grip that is generally known as a shackle grip on the top and bottom surfaces of the rail base flange. The action is the same at the end 15 of the bar relative to the top and bottom surfaces of the body portion of the wedging device. The inclined surface 10 of the wedge member draws the bar member in the direction of its length across the rail base, and forces the end 14 of the bar upon the adjacent flange of the rail. This wedging action also expands the turned-over end 15 and insures a powerful frictional grip which advances the U-shaped body of the wedging device upon the adjacent rail flange.

It will be noted in Figure 2 that the top surface of the anchor bar at the left of the point 13 is in frictional contact with the under surface of the rail flange.

The offset 18 has the action of a lever arm in twisting the anchor bar, which is an important function in anchoring the device. The inclined surface 10 also performs an important function in drawing the bar crosswise of the rail.

From the foregoing description it is clear that I have provided a two-piece rail anchor which is cheap in first cost, simple in construction and efficient in operation when applied in connection with a rail and tie.

A plurality of the devices illustrated will in use anchor the rails to the ties so they cannot move relative to the ties, and consequently the force or forces which cause creeping must be transmitted to several ties at the same time and at different points, thus distributing the energy so that the rails and ties will not move relative to the track ballast.

What I claim is:

1. The combination in a rail anchoring device, of an anchor bar having hooked ends and a lever, and a wedging device having an inclined surface adapted to engage said lever and twist the bar upon a rail flange and upon the wedging device.

2. The combination in an anchoring device, of a bar with turned-over ends and a lever, and a wedging device provided with means engaging the lever for twisting the bar, and also with means for moving the bar at the same time crosswise of the rail.

3. An anchoring device comprising a bar with turned-over ends and an offset constituting a lever, and a wedging device having a flange to engage a tie and an inclined surface to engage the offset of the bar.

4. An anchoring device comprising a bar with turned-over ends and a lever, and a wedging device having two inclined surfaces one to engage the said lever and the other to engage one of the turned-over ends of the bar.

5. The subject-matter of claim 4 wherein the device is provided with a flange to engage a cross tie.

6. The combination in an anchoring device, of a bar with hooked ends and a lever offset 18 in the body of the bar disposed horizontally relative to the longitudinal axis of the bar, and a wedging device having a flange at one end and two inclined surfaces one of said surfaces frictionally engaging the top surface of the offset when the parts are assembled.

7. A rail anchor comprising a rail base embracing member and a wedge member, the body surface of which inclines longitudinally of the rail when applied thereto and adapted to be forced between the bottom surface of the rail base and the top surface of said embracing member, whereby the embracing member is subjected to a torsional stress to force one end thereof into shackle gripping engagement with the top and bottom surfaces of the rail base.

8. A rail anchor comprising a rail base embracing bar and a wedge member adapted to be driven into wedging position between the base flange of the rail and said bar; the wedge member being formed on its bottom and side faces with tapered surfaces, whereby one end of the bar is flexed outwardly relative to the adjacent rail base flange and the body portion of said bar is subjected to a torsional stress.

9. A rail anchor comprising a metal bar formed at one end with a turned over portion adapted to grip the top and bottom surfaces of the rail base and formed at the other end with a turned over hooked portion adapted to embrace a wedge member adapted to be positioned between the said hooked over end portion and the adjacent edge of the rail base; the said wedge member being formed with a tapered bottom surface adapted to bear against the top surface of said bar, whereby the movement of said bar into gripping engagement with the said wedge member subjects the body portion to a torsional stress and moves the hooked end portion at one end of the anchor into gripping engagement with the top and bottom surfaces of the rail base.

10. A rail anchor consisting of a rail base embracing bar for engagement with one edge of a rail base and the upper surface of said bar being normally parallel, longitudinally of the rail, with the under surface of said rail base, and a wedging member formed with a tapered bottom surface adapted to be driven between the rail base and said top surface of said embracing bar, whereby said embracing bar is flexed to move said top surface thereof into flat gripping engagement with the tapered surface of said wedge member.

11. A rail anchor consisting of a rail base

- embracing bar formed at its ends with turned over hooked portions, one of which is adapted to grip one edge of a rail base and formed with the top surface of the bar disposed normally parallel longitudinally of the rail when the device is applied in its initial position on the rail base, and a wedge member formed with jaws for embracing the other edge of the rail base and adapted to be driven into gripping engagement between the rail base and the other turned over end of said embracing bar; the bottom and side surfaces of said wedge member being formed with tapered surfaces whereby the embracing bar is forced transversely of the rail base into tight gripping engagement therewith and is subjected to a torsional stress whereby the hooked portion at one end of the bar is forced into shackle gripping engagement with the top and bottom surfaces of the rail base.
- 5 10 15 20
- 10 In testimony whereof I affix my signature.

ADONIRAM J. COOK.
